UNITED STATES PATENT OFFICE.

ALBERT G. SCHERER, OF CHICAGO, ILLINOIS, ASSIGNOR TO THE EXCELSIOR STEEL FURNACE COMPANY, OF CHICAGO, ILLINOIS, A CORPORATION OF ILLINOIS.

STACK-HEAD FOR HOT-AIR STACKS OR CONDUITS.

1,141,492.

Specification of Letters Patent.

Patented June 1, 1915.

Application filed June 8, 1914. Serial No. 843,671.

To all whom it may concern:

Be it known that I, ALBERT G. SCHERER, a citizen of the United States, and resident of Chicago, in the county of Cook and State 5 of Illinois, have invented a new and useful Stack-Head for Hot-Air Stacks or Conduits, of which the following is a specification.

In the installation of the conduits for the 10 distribution of hot air in connection with a hot air heating system, the vertically disposed conduit are usually known as stack. It is the general practice to employ conduit of rectangular section so as to be able to install the same between the studding of the 15 walls. The conduit may be either single or double walled. It is desirable, and is the practice, to provide the vertical stack with register openings and for this purpose specially 20 formed sections of stack are provided and these sections are known as stack heads. A stack head may terminate the upper end of a stack, or, as is very often the case, the stack may be carried above the first head to 25 one or more upper stories. It will also be seen that when a stack is carried above a register opening the conduit may economically be reduced in section as the upper portion of the stack does not have to supply 30 the lower register.

It has heretofore, so far as I am aware, been necessary to manufacture and carry in stock a considerable number of different stack heads to meet the exigencies of different 35 installations.

It is the object of my present invention to design a single stack head which will serve either as a final termination of a stack, or will permit of the assembly therewith of the 40 same size or a choice of several smaller size conduits so as to extend the stack to an upper story.

I attain the above objects by means of the structure illustrated in the accompanying 45 drawing, in which:—

Figure 1 is a perspective of a stack head built in accordance with my invention, the same being shown with a closure covering the upper opening; Fig. 2 is a perspective 50 detail of one corner of the structure shown in Fig. 1 with a section of smaller sized conduit in assembly therewith; Fig. 3 is a vertical transverse sectional detail of the top of the stack head with a section of conduit 55 in assembly therewith; Fig. 4 is a longitudi-

dinal vertical sectional detail of the structure shown in Figs. 2 and 3; Fig. 5 is a modified construction of tongue for closing the openings between the end walls of sections of different width.

Similar reference characters refer to similar parts throughout the several views.

I have shown my invention embodied in a double wall stack head. The stack head comprises front, inner and outer walls 1, 1', and 1'', inner and outer side walls 2, 2, and 2', 2'', and inner and outer rear walls 3, 3'. What may be regarded as the upper forward portions 4, 4, of the side walls are sloped or tapered rearwardly, the top of the front walls terminating where the taper commences to form an opening in the stack with rearwardly inclined vertical edges for mounting a register.

The inner and outer walls are spaced 75 apart to permit of the circulation of air between the respective walls and the forward edges of the tapered portion of the inner and outer side walls are brought together by bending about a half inch or 80 thereabout of the outer wall inwardly upon a bevel until it meets the inner wall and then turning the edge of the inner wall outwardly and seaming it down over the edge of the outer wall.

The top of the register opening is formed as just described of inner and outer walls, 5 and 5, which run rearwardly until the end of the taper of the side walls, and then upwardly to form, in connection with the inner and outer side and rear walls, a means 90 for connecting a closure or another section of stack as may be desired.

The means supplied for securing a closure or another section of stack consists in bending the outer front side and rear walls inwardly to form a shoulder 6, to receive and support the outer wall of an adjoining section. The outer wall is carried upwardly from the shoulder 6, for a short distance 100 and is then turned inwardly and downwardly (as at 7 in Fig. 4) until the inner wall is reached. The outer wall is then carried upwardly against the inner wall to near the upper edge thereof where a ridge, 8, 105 of angular section is formed and the wall is then carried up and over the inner wall. The ridge 8 is for the purpose of locking the closure or an additional section in position.

In Fig. 1 I have shown the top of the 110

stack provided with a closure, 9, as will be necessary when the stack is not to be carried above the stack head.

In order to make it possible to assemble 5 stack sections of different dimensions with the opening in the top of the stack head, I provide a series of opposite transverse slits 10, in the front and rear walls about the opening in the top of the stack head which 10 extend approximately to the shoulder 6, so that the end walls of stack of less width may enter the slits 10, an area of the inner walls of the stack of less width being cut away at their respective corners 15 so that the side walls of such assembling sections will assemble and lock with the front and rear walls of the stack head in the usual manner. Such an assembly of the stack head with a section of stack of less 20 width, as above described, would leave an opening between the inner side walls of the stack head and the side walls of the section of narrower stack, and to close these openings, I secure by their lower edges to the 25 inner faces of the inner side walls the tongues 11, which may be flexed outwardly to extend within and come adjacent the inner end walls of the adjoining section, as shown in Figs. 3 and 4. The tongues 11 may 30 be soldered or secured in any convenient manner to the inner side walls of the stack head, or, as is shown in Fig. 5, a pocket 12 may be formed in the inner side walls into which can be inserted a properly shaped 35 piece of sheet metal 13, which may be readily cut to suit conditions on the job.

Having described my invention what I claim as new and desire to secure by Letters Patent, is:—

40. 1. A stack head for hot air stack comprising a casing of substantially rectangular cross section formed with a register opening and a plurality of openings for connection with sections of stack, the rim of one of said 45 openings being formed to enter an adjacent section of stack, said rim being provided with oppositely disposed slots for the reception of the walls of a section of lesser breadth, and tongues secured to the inner 50 surface of said stack head adjacent said last mentioned opening and adapted to be flexed to enter a section of less breadth.

55. 2. A stack head for hot air stack comprising a casing of substantially rectangular cross section formed with a register opening and a plurality of opening for connection with sections of stack, the rim of one

of said openings being formed to enter and lock with an adjacent section of stack, said rim being provided with oppositely disposed 60 slots for the reception of the walls of a section of lesser breadth, and tongues secured to the inner surface of said stack head adjacent said last mentioned opening and adapted to be flexed to enter a section of 65 less breadth.

3. A stack head for hot air stack comprising a double wall casing of substantially rectangular cross section formed with a register opening and a plurality of openings 70 for connection with sections of stack, the rim of one of said openings being formed to enter an adjacent section of stack, said rim being provided with oppositely disposed slots for the reception of the walls of a section of lesser breadth, and tongues secured 75 to the inner surface of said stack head adjacent said last mentioned opening and adapted to be flexed to enter a section of less breadth.

4. A stack head for hot air stack comprising a double wall casing of substantially rectangular cross section formed with a register opening and a plurality of openings 80 for connection with sections of stack, the rim of one of said openings being formed to enter and lock with an adjacent section of stack, said rim being provided with oppositely disposed slots for the reception of the wall of a section of lesser breadth, and tongues secured 85 to the inner surface of said stack head adjacent said last mentioned opening and adapted to be flexed to enter a section of less breadth.

5. A stack comprising a section of casing 95 of substantially rectangular cross section formed with a plurality of openings for connection with other sections of stack, the rim of one of said openings being formed to enter an adjacent section of stack, said rim 100 being provided with oppositely disposed slots for the reception of the walls of a section of lesser breadth, and tongues secured to the inner surface of said section of stack adjacent said last mentioned opening and 105 adapted to be flexed to enter a section of less breadth.

In testimony whereof I affix my signature in the presence of two witnesses.

ALBERT G. SCHERER.
